ROBERT ALKAN AND GEORGES LESOURD, OF PARIS, FRANCE.

APPARATUS FOR THROWING PROJECTILES FROM AIRCRAFT.

Application filed March 5, 1926, Serial No. 92,493, and in France March 9, 1925.

This invention relates to an apparatus specially designed for automatically dropping projectiles from an aircraft in controlling the operation of the fuzes of the same.

5 The apparatus is constructed so that

(1) the projectile can be released having its fuzes primed, e. g. in leaving the safety devices of these fuzes attached to the bomb-thrower,

10 (2) the projectile can be released having its fuzes not primed, e. g. to drop with the projectile the safety devices on the fuzes,

(3) the throwing of the projectile in the one or other manner may be prepared at any 15 moment, and the manner of throwing may be altered as long as the releasing manoeuvre has not taken place.

With this object in view the apparatus comprises:

20 (a) a main releasing mechanism,

(b) auxiliary mechanisms controlling the safety device of the fuzes,

(c) a driving mechanism ensuring the junction and the working of the main releasing mechanism and of the auxiliary releasing mechanism.

An embodiment of the invention is shown, by way of example, in the accompanying drawings, in which—

30 Fig. 1 shows in perspective view the total arrangement of the apparatus in the position in which the projectile is clenched.

Fig. 2 is a similar view showing the position in which the projectile is released its 35 fuze being primed.

Fig. 3 is a similar view showing the position in which the projectile is clenched but after the previous preparation for the throwing of the projectile its fuze being not 40 primed.

Fig. 4 shows in similar view the position after the releasing of the ring of the safety device.

Fig. 5 shows the hook for releasing the 45 projectile, in elevation and in the clenching position.

Fig. 6 shows this hook in the releasing position.

The apparatus comprises essentially: 50 (1) the main releasing mechanism to the hook of which the projectile 18 is suspended and the operation of which is controlled by a cam 1 which controls the principal positions of locking (Fig. 5) and of releasing 55 (Fig. 6).

(2) the auxiliary releasing mechanism

which is composed of a hook 2 holding the ring 19 attached to the safety mechanism of the fuze and of a lever 3 pulled back by a spring and which prevents said ring from dropping off the hook 2 and which further may push this ring off when the hook 2 is pulled back by the action of the driving rod 4.

(3) the main drive for the cam 1 consisting of an axle 5 to which rotation is communicated from a distance and which acts upon the cam 1 by means of a lever 20 at its upper end, and through the intermediary of two cranks 6 and 7 and a rod 8 forming 70 parallelogram.

On the main driving axle 5 an eccentric 21 is keyed which, through the intermediary of a connecting rod 9 communicates an oscillating movement to a lever 10 to which it is connected and which is pivotally mounted at 11 on the rod 4 which controls the auxiliary releaser 2, 3. A spring 12 serves to maintain the rod 4 in the position in which the auxiliary releaser 2, 3 is closed.

A second driving axle 13 serves to move a crank 14 carrying a roller 15 and held in its position of rest by the action of a spring 16, so that the roller 15 is in the lower position shown in Figs. 1 and 2.

If, under these conditions, the main driving axle 5 is operated by the lever 20 being pulled in the direction indicated by arrow 22, this driving axle 5, on the one hand, rotates the cam 1 through the intermediary of rod 8 and, on the other hand, acts through the intermediary of its eccentric 21 and crank 9 upon the lever 10 which, having no other supporting point but its axle 11 on rod 4 executes the same movement as the eccentric 95 and pivots around the axle 11 which together with rod 4 is securely held by the action of the spring 12. In this case only the main releaser operated by cam 1 works, the auxiliary releaser 2, 3 remains closed and, the ring 19 of the safety device of the fuze remaining attached the safety device is separated from the fuze and the projectile 18 drops having its fuze primed (Fig. 2).

If, however, the auxiliary driving axle 13 is first rotated by a pull exerted upon the lever 23 in the direction of arrow 24 (Figs. 3 and 4) the roller 15 will adopt the raised position indicated in these Figs. 3 and 4.

If subsequently the main driving axle is 110 operated the cam 1 and eccentric 21 will be rotated as in the first case and lever 10,

pivoting around its axle 11 will come in contact with roller 15 which forms a stationary abutment. The lever 10 continuing to oscillate under the action of the crank 9, the action of which is stronger than the action of spring 12, the rod 4 will be shifted and the auxiliary releaser will open (Fig. 4). It is evident, that by providing for a convenient jamming of the elements it will be possible to obtain the opening of the auxiliary releaser 2, 3 prior to that of the main releaser. The ring 19 of the safety device will therefore be liberated prior to the bomb 18 dropping from the aircraft and it will be thrown having its fuze not primed.

This device may be applied to all fuzes of one and the same projectile.

The above described mechanisms are given by way of example only and might be modified without departing from the characteristic features of the invention these features being capable to be applied to apparatus comprising main or auxiliary releasing mechanisms of any type for supporting projectiles in vertical or horizontal position.

We claim:

1. An apparatus for throwing projectiles from aircraft, comprising in combination a main releasing device for the dropping of the projectiles and consisting of a hook pivotally mounted on the frame of the apparatus and carrying the projectile and of a pivotable L-shaped arm normally holding said hook in the inoperative position, means for operating said main releasing device, and consisting of a cam rotatably located in said L-shaped arm of the supporting hook, a crank on the axle of said cam, a driving axle to be rotated from a distance, a crank on said rotatable axle, a crank on the axle of said cam, a spring-controlled shiftable rod connecting said two cranks, an auxiliary releasing device for releasing the safety device of the fuze, and auxiliary means for operating said auxiliary releasing device dependent upon said main releasing device in order that the projectile may be thrown either with fuze not primed or with primed fuze, said means consisting of an eccentric keyed on the lower end of said driving axle, a crank on said eccentric, a spring-controlled rod attached to the upper end of said auxiliary releasing device, a lever pivotally mounted at the upper end of said connecting rod and engaging with said crank of said eccentric, and of a spring for holding said connecting rod in the position of rest, and auxiliary driving means independent of said means for operating said main releasing device the position of which last mentioned auxiliary driving means can be altered at any moment as long as said main driving means have not been operated and without exerting any action upon said main and auxiliary releasing devices, said auxiliary driving means consisting of an axle adapted to be rotated from a distance, a crank at the lower end of said axle, a spring holding said crank in the normal position said spring being feebler than said spring of said rod of the means for operating said auxiliary releasing device, and a roller in the outer end of said crank designed to be brought into the path of said pivotable lever in the crank of said cam of the main driving axle so that said lever can shift said rod of the auxiliary driving device to release the ring of the fuze of the projectile prior to the release of said projectile.
2. An apparatus for throwing projectiles from aircraft, comprising in combination a main releasing device for the dropping of the projectiles, and consisting of a hook pivotally mounted on the frame of the apparatus and carrying the projectile and of a pivotable L-shaped arm normally holding said hook in the operative position, means for operating said main releasing device, and consisting of a cam rotatably located in said L-shaped arm of the supporting hook, a crank on the axle of said cam, a driving axle to be rotated from a distance, a crank on said rotatable axle, a crank on the axle of said cam, a spring-controlled shiftable rod connecting said two cranks, an auxiliary releasing device for releasing the safety device of the fuze, and auxiliary means for operating said auxiliary releasing device dependent upon said main releasing device in order that the projectile may be thrown either with fuze not primed or with primed fuze, said means consisting of an eccentric keyed on the lower end of said driving axle, a crank on said eccentric, a spring-controlled rod attached to the upper end of said auxiliary releasing device, a lever pivotally mounted at the upper end of said connecting rod and engaging with said crank of said eccentric, and of a spring for holding said connecting rod in the position of rest, and auxiliary driving means independent of said means for operating said main releasing device the position of which last mentioned auxiliary driving means can be altered at any moment as long as said main driving means have not been operated and without exerting any action upon said main and auxiliary releasing devices, said auxiliary driving means consisting of an axle adapted to be rotated from a distance, a crank at the lower end of said axle, a spring holding said crank in the normal position said spring being feebler than said spring of said rod of the means for operating said auxiliary releasing device, and a roller in the outer end of said crank designed to be brought into the path of said pivotable lever in the crank of said cam of the main driving axle so that said lever can shift said rod of the auxiliary driving device to release the ring of the fuze of the projectile prior to the release of said projectile.

mounted at the upper end of said connecting rod and engaging with said crank of said eccentric, and a spring for holding said connecting rod in the position of rest.

2. An apparatus for throwing projectiles from aircraft, comprising in combination a main releasing device for the dropping of the projectiles, and consisting of a hook pivotally mounted on the frame of the apparatus and carrying the projectile and of a pivotable L-shaped arm normally holding said hook in the operative position, means for operating said main releasing device, and consisting of a cam rotatably located in said L-shaped arm of the supporting hook, a crank on the axle of said cam, a driving axle to be rotated from a distance, a crank on said rotatable axle, a crank on the axle of said cam, a spring-controlled shiftable rod connecting said two cranks, an auxiliary releasing device for releasing the safety device of the fuze, and auxiliary means for operating said auxiliary releasing device dependent upon said main releasing device in order that the projectile may be thrown either with fuze not primed or with primed fuze, said means consisting of an eccentric keyed on the lower end of said driving axle, a crank on said eccentric, a spring-controlled rod attached to the upper end of said auxiliary releasing device, a lever pivotally mounted at the upper end of said connecting rod and engaging with said crank of said eccentric, and of a spring for holding said connecting rod in the position of rest, and auxiliary driving means independent of said means for operating said main releasing device the position of which last mentioned auxiliary driving means can be altered at any moment as long as said main driving means have not been operated and without exerting any action upon said main and auxiliary releasing devices, said auxiliary driving means consisting of an axle adapted to be rotated from a distance, a crank at the lower end of said axle, a spring holding said crank in the normal position said spring being feebler than said spring of said rod of the means for operating said auxiliary releasing device, and a roller in the outer end of said crank designed to be brought into the path of said pivotable lever in the crank of said cam of the main driving axle so that said lever can shift said rod of the auxiliary driving device to release the ring of the fuze of the projectile prior to the release of said projectile.

In testimony whereof we affix our signatures.

ROBERT ALKAN.
GEORGES LESOURD.
